UNITED STATES PATENT OFFICE.

BENJAMIN J. COHON, OF WESTWOOD, NEW JERSEY, ASSIGNOR OF ONE-HALF TO LOUIS MOSKOWITZ, OF BAYONNE, NEW JERSEY.

LATCHING DEVICE.

1,339,320.

Specification of Letters Patent. Patented May 4, 1920.

Application filed March 21, 1916. Serial No. 85,545.

To all whom it may concern:

Be it known that I, BENJAMIN J. COHON, a citizen of the United States, residing at Westwood, in the county of Bergen and 5 State of New Jersey, have invented certain new and useful Improvements in Latching Devices, of which the following is a specification.

My invention relates to an improvement 10 in latches for doors and the like; and has for its object to provide a latch that is of simple and inexpensive construction, capable of being operated with ease and certainty, and constituted of relatively few 15 parts that coact in such a way as to reduce the likelihood of the latch being opened from without by unauthorized persons seeking to unfasten the same.

On the drawings, which illustrate an embodiment of my invention:

Figure 1 is a view of a latch made in accordance with my invention as it appears when the parts are in open position;

Fig. 2 is a similar view, showing the latch 25 with the latch bolt shot, to secure a door or the like upon which the latch is employed;

Fig. 3 is a cross section taken on the line 3—3 of Fig. 1; and

Fig. 4 is a view of a detail.

The same numerals of reference are used 30 to identify the same parts throughout this specification.

The mechanism of my latch comprises a carrier 1 and a bolt 2 in a support or casing 3. The casing will be located on a door or the like 4, and the bolt 3 will have a lateral projection or catch 5 at its forward end to engage with a striker plate 6. This plate will of course be fixed to the frame of the 40 door. The adjacent end of the casing 1 will have an aperture 7, through which the bolt 2 will be moved to enable the catch 5 to enter a corresponding opening 8 in the plate 6; and, with the casing mounted as 45 shown, be dropped below the lower edge of this opening, in order to hold the door shut. Normally the catch 5 will be out of alinement with the aperture 7, and it is first moved into such alinement, then out of the 50 casing, and through the plate 6, and then behind the edge of the opening 8, in a manner that will be hereinafter set forth.

The carrier 1 is reciprocable in the casing 3 toward and from the aperture 7; and 55 moves between the part of the casing shown

as the top in the drawings and a guide lug 9. The edge of the carrier engaging the casing may be bent over, or otherwise provided with a flange 10; and its rear end may be bent up, or otherwise provided with 60 a lug or flange 11, to which is fixed a guide rod 12. This rod passes through a hole in the rear end of the casing and is surrounded with a spring 13 normally acting to impel the carrier toward the aperture 7. The 65 edge engaging the guide lug 9 will have a recess 14 therein near the front end of the carrier for a purpose which will be explained presently. The rod 12 may be omitted and the spring 13 used alone. 70

In order to enable the bolt 2 to move with respect to the carrier, I provide slots 15 in the bolt and cause these slots to be engaged by studs 16 on the carrier 2. The slots extend transversely of the line of movement 75 of the carrier, and ordinary bolts or screws engaging threaded holes in the carrier may be used to serve the purpose of the studs just mentioned. The edges of the bolt parallel to the line of movement of the carrier 80 may be provided with flanges 17, as by turning or bending these edges, and the flanges in question may be perforated to receive guide rods 18 made fast to the flange 10. These rods will each be encircled by a 85 spring 19 between the upper flange on the bolt and the flange 10, to press the bolt away from the flange 10. When the carrier moves toward or from the aperture 7, the bolt of course moves in unison with it; 90 and the bolt can thus be actuated to move the catch through the aperture 7 and opening 8 in the plate 6.

The casing is also perforated to give entrance to a shaft 20, carrying cams 21 and 95 22. The cam 21 is fixed to the shaft and when the shaft is turned clockwise, as shown in the drawings, the nose 23 of this cam will act to force the bolt to move with respect to the carrier, against the force of 100 the springs 19. The cam 22, on the other hand, is loose on the shaft, but has shoulders 24 and 25 adapted to be engaged by projections 26 and 27 respectively on the cam 21. These projections are not as far 105 apart as the shoulders 24 and 25, and may be replaced by a single projection if desired.

When the bolt is withdrawn the parts of the latch are as in Fig. 1. In operation, the shaft is turned and the cam 21 moves the 110

bolt with respect to the carrier, against the springs 19, to bring the catch 5 in line with the aperture 7. At this time the carrier is stationary, and the bolt simply moves 5 on the carrier across the line of movement of the latter. When the nose of the cam 21 has pushed the bolt up as far as it will go, the forward projection 26 on the cam 21 will engage with the shoulder 24 of the cam 10 22; and as this cam has its nose in the recess 14 of the carrier, the further actuation of the cam 21 will throw the carrier and the bolt in unison toward the aperture 7, and make the catch go through the plate 6. 15 The spring 13 on the rod 12 may of itself be made strong enough to move the carrier through the aperture 7 as soon as the catch 5 clears the lower edge of the aperture 7.

Further motion of the cam 21 now advances 20 the nose 23 and allows the springs 19 to force the bolt downward and the catch behind the lower edge of the opening in the striker plate. The adjacent edge of the bolt will now come into contact with a straight 25 portion of the cam 21 to the rear of the nose 23; and the springs 19 will not only hold the bolt, but also the cam 21.

It will be noted that the shaft 20 carries 30 a knob 28 on its outer end, and is held in a bearing 29 which has screw-threaded engagement with the casing and extends from the casing out to the knob. This knob is recessed on the side that is presented to the casing, as by having an annular groove 30 to the casing, in which the outer end of the bearing is received. Hence the portion of the shaft outside of the casing is covered and protected, and access to this part of the shaft is prevented. Consequently, the lock 35 40 cannot be opened except by turning the knob; for any one boring through the door near the casing and trying to engage the shaft between the casing and the knob mechanically, to turn it, will find the lock 45 cannot be manipulated in such a way. The same result might be obtained by mounting the element 29 loosely on the shaft without fixing it to the casing. The groove 30 is 50 preferably concentric with the shaft 20; and the knob 28 should have that one of its sides or faces which is turned toward the casing, made substantially flat, or otherwise shaped so that the peripheral portions of that face are no farther removed from the casing than 55 the portions adjacent the groove 30; so as to afford no hold on the side adjacent the casing.

The knob will of course be on the inner side of the door having the lock mechanism 60 thereon, and in Figs. 1 and 2 the lock is

shown as if viewed from that side. By making the bearing 29 detachable, the casing can be mounted not only on the side of the door, but also in a mortise provided in the edge thereof. The groove 30 will of course always receive the end of the bearing 29 loosely.

To withdraw the bolt, the shaft 20 is turned in the reverse direction. The cam 21 first shifts the catch 5 into alignment with 70 the aperture 7 and the opening 8; and the projection 27 on the cam 21 engages the shoulder 25 on the cam 22 to return both the bolt and the carrier into the casing.

From the above description it will be apparent that my latch is well adapted to serve the purpose for which it is intended; and while I have shown but one construction, the principle of my lock may be embodied in other combinations of parts that are similar in effect, and I therefore reserve the right to vary the shape, size and arrangement of parts to the full extent indicated by the meanings of the terms in which the claims are expressed.

Having described my invention, what I believe to be new, and desire to secure and protect by Letters Patent of the United States is:

1. The combination of a movable carrier, a bolt mounted on the carrier and movable across the same, a spring and a cam for controlling the movement of the bolt with respect to the carrier, and a spring and a cam for effecting movement of the carrier and bolt in unison, said bolt being first moved in one direction relative to the carrier, and then in unison therewith, and finally relative to the carrier in the opposite direction to afford a locking effect.

2. The combination of a movable carrier, a bolt mounted on the carrier and movable across the same, a spring and a cam for controlling the movement of the bolt with respect to the carrier, a shaft on which the cam is rigidly mounted, and a spring and a second cam for effecting movement of the bolt and the carrier in unison, the second cam being loosely mounted on the shaft and being engaged to be actuated by the first cam, the bolt being first moved in one direction with respect to the carrier, then in unison therewith, and then finally with respect to the carrier opposite to the first direction to afford a latching effect.

In testimony whereof I have signed my name to this specification this 1st day of March, 1916.

BENJAMIN J. COHON.
